UNITED STATES PATENT OFFICE.

BENJAMIN SCARLES, OF CLINTON, MASSACHUSETTS, ASSIGNOR OF ONE-HALF
TO THE CLINTON WIRE CLOTH COMPANY, OF SAME PLACE.

MACHINE FOR THE MANUFACTURE OF WIRE-NETTING.

SPECIFICATION forming part of Letters Patent No. 387,739, dated August 14, 1888.

Application filed September 9, 1887. Serial No. 249,917. (No model.)

To all whom it may concern:

Be it known that I, BENJAMIN SCARLES, a subject of the Queen of Great Britain, but temporarily residing at Clinton, county of Worcester, and State of Massachusetts, have invented 5 an Improvement in Machines for the Manufacture of Wire-Netting, of which the following description, in connection with the accompanying drawings, is a specification, like letters on the drawings representing like parts.

In another application, Serial No. 220,585, filed by me on the 3d day of December, 1886, I have shown and described a mechanism for the manufacture of wire-netting wherein the 15 twist in the wire between two meshes in the direction of the length of the netting is in the same direction, the twisting-segments being rotated in one direction during the formation of one transverse row of twists, and in the opposite direction for the formation of the next 20 transverse row of twists, the crank actuating the rack-bar for rotating the twisting-segments being so set on the shaft carrying it that the travel of the crank about the upper half of the 25 arc in which it is turned is such as to move the rack in but one direction while one transverse row of twists is being made, the rotation of the crank through the lower half of the arc in which it moves taking place when the next 30 transverse row of twists is being made, thus twisting the alternate transverse rows of twists in opposite directions.

In the manufacture of netting in the manner described it is necessary that every alternate 35 wire proceed from a cop which is adapted to be carried entirely around the wire with which it is to be twisted.

Winding one set of wires into cops to be placed into the tubes, and also winding the 40 other set of wires upon small bobbins, entails considerable expense, and also makes the machine more complicated and expensive.

Herein I have devised mechanism whereby the wires to be twisted into netting may be 45 used directly from the bundles as taken from the "wire drawing block."

In the process of drawing wire the molecules are arranged in regular order, and any bending of the wire disturbs said arrangement and 50 injures the texture of the wire in proportion to the extent of the disarrangement. If wire is twisted a great number of times in one di-

rection, the molecular disturbance is greater than if twisted half in one and half in the opposite direction. By my mode of twisting the 55 wire in opposite directions in each transverse row of twists I am enabled to make netting of a low grade of wire, the netting when made being of as good quality as that made of a better grade of wire when twisted in one direction only in each transverse row.

To enable the wires to be twisted in opposite directions in each transverse row of twists, I have so placed the crank which moves the rack-bar for operating the twisting-segments 65 that the said rack-bar is compelled to complete its stroke in one and then in the reverse direction during the formation of each transverse row of twists.

Preferably the crank for moving the rack-bar will be so placed as to travel from its top to its bottom center, or vice versa, such movement of the said crank causing the twisting-segments to be rotated in one direction while the crank travels through substantially ninety 75 degrees, and in the opposite direction while the crank travels through a second ninety degrees.

The machine herein to be described has been provided with a gripping mechanism, whereby 80 the wires in one transverse row of twists, having been twisted together for the proper number of turns, are held while the twisting-segments are reversed in their rotation to twist the wires in the opposite direction. 85

The act of twisting the wires in the reverse direction, as herein described in the formation of each transverse row of twists, enables the twist put into the wires between the delivery-orifices of the twisting-segments and the bundles of wire to be taken out, so that the said wires, each transverse row of twists having been completed, are free to be moved laterally independently, in order that the said wires in the formation of the next transverse row of 95 twists may be twisted with other wires to the right and left, as it is obvious is necessary in the formation of netting of the class referred to.

To enable the netting to be made stronger, 100 or to enable a selvage to be made at any point in the width of the machine, I have provided the twisting-segments with two or, it may be, more openings for two or more independent

or auxiliary wires, whereby, when desired, any one of the said segments may be provided with an extra wire, which will be twisted in with the regular wires carried by the said segments

5 when the wires are being twisted together, the said auxiliary wire lying parallel with the wire carried in the same segment between the points where the wires are twisted together.

My invention consists, essentially, in the combination, with twisting-segments to receive the wires to be twisted and means, substantially as will be described, for rotating the said segments in one and then in an opposite direction during the formation of each transverse row of 15 twists, of gripping mechanism, substantially as will be described, to hold the wires previously twisted in one direction while they are being twisted in the reverse direction; also, in the combination, with twisting-segments 20 to receive the wires to be twisted and means, substantially as will be described, for rotating the said segments in one and then in an opposite direction during the formation of each transverse row of twists, of pins to engage the wires just before the reverse twist is to be put 25 into the wires, to operate substantially as will be described.

Other features of my invention will be set forth in the claims at the end of this specification.

Figure 1 in front elevation represents a sufficient portion of a wire-netting machine to enable my present invention to be understood, some of the duplicated or like parts being 35 omitted to avoid confusion on the drawings. Fig. 2 is a left-hand end elevation of the machine shown in Fig. 1. Fig. 3 is a section of Fig. 1 in the dotted line $x-x$, looking toward the right, the said figure showing the first part 40 of the twist as taking place, the gripping mechanism being shown as open; Fig. 4, a partial right-hand elevation of Fig. 1, chiefly to show the mechanism for opening the gripping mechanism to be described, and also the take-up mechanism. Fig. 5 is a horizontal longitudinal section of the carriages and twisting-segments. Fig. 6 is a broken plan view and partial section of the carriages, the said figure showing the gripping mechanism and some of 50 the devices employed to move the said carriages and the jaws of the gripping mechanism; Fig. 7, a partial section of Fig. 6 in the line x^2-x^2 . Fig. 8 is a plan view similar to Fig. 6, showing a portion of one of the carriages and the gripping mechanism omitted from Fig. 6, the said figure also showing the slide for moving the rack, the said slide having a cam-surface to effect the closing of the jaws of the gripping mechanism. Fig. 9 shows, on an 55 enlarged scale, two wires twisted together in opposite directions; and Fig. 10 is an enlarged section of one of the jaws, to show clearly, as cannot be done in Fig. 3, the longitudinally-corrugated face of the jaw to thus crimp the 60 wire.

The frame-work A, the mesh-roll B', the roll 42, the pulley A⁴, the shaft A², the belt A³,

the take-up roll H³, the crank G⁵, the gears B⁵ B⁴ B³, the shaft B², the finger 35, the shaft A⁷, the beveled gears A⁵ A⁶, the worm 39, 7c the worm-gear 40, engaged by it and fast to the roll 42, the pinion 37, sleeve 38, projection 36 thereon, the carriages D and E, the rack-bar m, the uprights C², attached to the carriage D at one end, the cam C, the rollers 75 c' e' on the studs 2, the gear 44, the pulley H, the lever H⁵, the belt H', the pulley H², the slide G, having the screws m³ m⁴, to act on the projection m² of the rack-bar m, the slotted guide 82 for the said slide, the adjustable 8c screws 4, the tension mechanism or rolls f⁴ f⁵ f⁶ f⁷, the gibs h, the adjusting-screws h', and the oscillating bolts 25, holding the journals of the rolls f⁵ f⁶, are all substantially as in my application, Serial No. 220,585, filed on the 85 3d day of December, 1886, wherein like parts are designated by like letters.

Herein the carriage E has erected upon it an ear, C²², which is provided with friction-rollers c^x and c^{xx}, which are acted upon by a second cam, C²³, fast on the same shaft A⁷, the said cam C²³ being, however, set on the said shaft diametrically opposite the cam C, so that the said carriages shall be moved simultaneously in opposite directions, each carriage remaining, however, stationary for two short periods during each revolution of the shaft A⁷.

In the application referred to the carriage E was driven from the carriage D through the intervention of an upright shaft having 10c arms. In the application referred to the slide G was moved by an adjustable connecting-rod attached to an auxiliary slide, the latter being operated from the crank G⁵ by a pitman, but herein the slide G is connected directly to the 105 crank G⁵ in an adjustable manner by an adjustable link, G². Herein the screws or other suitable projections, m³ m⁴, of the slide G act against the projection m² of the slide M, and move it with the said slide, providing, however, for a certain amount of lost motion, as in the application referred to.

I have herein marked the twisting-segments by the letters a and b, the same letters being designated to mark the twisting-segments carried by the carriages D and E in the said application. These segments, as the segments in the said application, have semi-gears, which are engaged by the rack-bar m, and the said segments do not differ from the segments shown 115 in the said application except in that they have or may have two or more wire-passages instead of one, as in the said application, two or more passages being provided in order that any one or more of the several segments may 120 carry two or more wires, as is desirable, when, for instance, the netting needs to be strengthened at any one point, or when, for instance, it is desired to make a selvage at any one or more points across the width of the machine, 125 so as to make two or more longitudinal strips of netting upon the same machine. Each of these twisting-segments are herein shown as 130 provided with wires 101 and 102, taken, re-

spectively, from suitable bundles on creels 103 and 104, the said creels having removable heads, in order that the bundles of wire taken from the wire-drawing machine may be readily placed upon the studs of the creels. These creels are supported independently upon suitable uprights, as 105, and the wires 101 and 102 are passed between the tension-rolls $f^5 f^6 f^7$, and thence through the twisting-segments, the wire 101 being carried by the twisting-segment *a* and the wire 102 by the twisting-segment *b*, and, issuing from the said segments, the said wires are twisted together to form transverse rows of twist across the netting, and then by shifting the carriages and feeding the wires longitudinally a succeeding row of transverse twists is formed with a row of open meshes between.

In the application referred to the rack *m* is moved in but one direction while each transverse row of twists is being put into the wire; but herein I have made provision whereby the rack *m*, or the device employed to rotate the twisting-segments when opposite each other, is made to rotate the said segments in one and then in the opposite direction for a greater or less number of times during the formation of each transverse row of twists, thus twisting the said wires in each transverse row of twists in opposite directions. To do this as embodied in this present instance of my invention, I have so set the crank G^5 upon or with relation to the shaft A^7 , which is instrumental in moving the carriages, that the said crank travels from its upper to its lower center during the formation of each transverse row of twists, such movement of the crank causing the rack *m*, through the slide *G* and connecting-rod G^2 , to rotate the twisting-segments two or more times in one direction and on the backstroke of the rack to rotate the said twisting-segments two or more times in the reverse direction.

The rotation of the twisting-segments in reverse directions during the formation of one transverse row of twists in the netting is, I believe, novel with myself, and therefore I do not desire to limit my invention to the exact mechanical devices herein shown for effecting such rotation of the said twisting-segments, and instead of the devices herein shown for such purpose I may employ any other well-known or equivalent mechanism capable of accomplishing the desired result. When the twisting is to be reversed, as stated, it is necessary that the partially-twisted wires be clamped or held just at or before the direction of the twisting-segments is reversed. To do this, I have provided the carriages *D* and *E* with a gripping mechanism consisting, essentially, of jaws 107 and 108, the said jaws having combined with them, or with one of them, suitable mechanical appliances whereby they may be moved, one or the other of them, to clamp or hold the wires between them.

As herein shown, the jaw 108 is fixed to the carriage *E* by screws 109; but the jaw 107 is provided at its under side (see Fig. 1) with a

dovetailed groove, as 110, which receives within it a correspondingly-shaped projection, 112, attached to or forming part of the carriage *D*, so that the said jaw may be moved transversely with relation to the said carriage. The jaw 107 has erected upon it near its ends suitable swivel-posts, 113, to the heads of which are pivoted links 114, which in turn are jointed to arms 115 of a rock-shaft, 116, the said rock-shaft having suitable bearings, 117, upon the frame-work, and having at its outer end an arm, 118, upon which is attached in an adjustable manner the weight 119; or it might be a spring, the purpose of which is to move the jaw 107 away from the jaw 108 to release the gripping mechanism from the wires when the same are to be fed for the formation of the next row of meshes.

To cause the jaw 107 to be moved toward the jaw 108, so as at the proper time to grip the twisted wires, I shall provide the said jaw at one or more places, preferably several, with arms 120, provided with friction-rolls 121, each of the said arms being suitably pivoted, as at 122, to the jaw, and being acted upon by a spring, 123, which normally keeps the jaw pressed against a stop, 124, attached to the said jaw.

The slide *G* has attached to it by screws 125 a bar, 126, (see Fig. 8,) having a cam-surface, as 127, there being as many cam surfaces or depressions as there are arms 120.

When the first half of the twist for each transverse row of twists is being made, the rack *m* is supposed to be moved in the direction of the arrow 128, and in such direction of movement, the slide *G* moving in the same direction, the cam-surface 127 is not effective to push the jaw 107 forward to clamp the wire, for the arm 120 yields against the spring 123 before the friction on the jaw 107 is overcome, and consequently the said jaws are left open, as in Figs. 2 and 3; but during the reverse movement of the slide *G*, as soon as the roll 121 comes opposite or into the cam space 127, then the said cam, acting on the roll 121, quickly and positively moves the said jaw forward to clamp firmly and hold the twisted parts of the wire between itself and the jaws opposed to it, and the said jaw which is so moved is so held forward during the time that the reverse twist is taking place, after which the bar 126 is again moved until the roll comes opposite another cam surface or depression, when the weight 119 referred to restores the jaw 107 to its normal open position. The acting-faces of the jaws will in practice be grooved longitudinally in order that they may better and more securely hold the wires and prevent them from being drawn laterally when the change of twist occurs. The shape of the contiguous edges of the jaws 107 and 108 is best shown in Fig. 3, and therein it will be noticed that the jaw 107 has at a point immediately below its clamping-face a series of pins or studs, 130, which, when the jaws are closed upon the wire, enter the space between the two wires, being twisted to

gether and remaining there until the reverse twist is completed, when the pin by the opening of the jaws is withdrawn. These pins are employed only when it is desired to leave a small eye for the reception of a wire to bridge the central part of the mesh. This pin adds materially to prevent the untwisting of the first part of the twist when the reverse twist is being put in, but is unnecessary, for the jaws are effective without the pins to prevent the untwisting of the wire when the reverse twist is being put in.

In practice, the acting-faces of the jaws will be more or less deep, according to the length of the twisted part of the wire between the meshes, and in some instances the jaws will be from an inch to an inch and a half deep.

In Fig. 10, on a larger scale, I have shown one of the jaws as provided with several corrugations, the other jaw in practice having a like number of corrugations, so that when the jaws are forced together upon the twisted wire the same is crimped, as it were, between the meshes which gives stiffness to the netting.

It will be obvious that when the machine is to be used to form several narrow strips of wire-netting the wires will be entirely omitted from some of the segments, and in case a selvage containing two wires is desired for each of the said strips, then those segments carrying the edge-forming wires will be provided with extra independent wires.

I claim—

1. In a machine for the manufacture of wire-netting, a series of twisting-segments and means to rotate them, substantially as described, in opposite directions during the formation of each transverse row of twists, combined with gripping mechanism, substantially as described, to hold the wires previously twisted in one direction while they are being twisted in the reverse direction, substantially as described.

2. In a machine for the manufacture of wire-netting, the combination, with twisting-segments to receive the wires to be twisted and means, substantially as described, for rotating the said segments in one and then in an opposite direction during the formation of each transverse row of twists, of a series of pins and means to support them, the said pins entering between the wires after the completion of the first portion of the twist in each line of meshes and holding the wires while the reverse twist is taking place, substantially as described.

3. In a machine for the manufacture of wire-netting, carriages D E, and ears C and C²², attached, respectively, to them, and projections on said ears, combined with the shaft A⁷, provided with two cams set opposite to each other to intermittently but positively move the said carriages in opposite directions, substantially as described.

4. In a machine for the manufacture of wire-netting, two reciprocating carriages, D E, combined with twisting-segments, some of which

have two or more passages for auxiliary wires, whereby some of the longitudinally-twisted strands extended through the netting may contain two wires which are twisted with a third wire at the twisting-point, leaving the two wires carried by one segment parallel between the said twisting-points, substantially as described.

5. In a machine for the manufacture of wire-netting, the mesh-roller, two or more carriages, D E, means to reciprocate them in opposite directions at the proper time, two series of twisting-segments carried by the said carriages, and means to rotate the said twisting-segments in one and then in the reverse direction during the formation of each transverse row of twists, combined with a tension spring held or yielding arm, 120, which stands rigidly when the jaw 107 is being moved toward the jaw 108, the cam-bar at such time being moved longitudinally, the said arm yielding when the cam-bar is moved to regulate the tension upon the wires passing to the said segments, substantially as described.

6. In a machine for the manufacture of wire-netting, the carriages D E, their twisting-segments, and means to rotate the said twisting-segments in one and then in a reverse direction during the formation of each transverse row of twists, combined with jaws 107 and a series of pins, 130, the latter to enter between the said wires after they have been twisted in one direction and to hold them while the wires are being twisted in the opposite direction, substantially as described.

7. In a machine for the manufacture of wire-netting, the carriages D E, the twisting-segments therein, and means to rotate them, combined with gripping mechanism having jaws corrugated longitudinally to crimp the twisted wire, substantially as described.

8. In a machine for the manufacture of wire-netting, the reciprocating carriages D E, the twisting-segments a b therein, and means to rotate them, and the jaws 107 and 108 of the gripping mechanism, combined with a cam-bar, 126, means to move it, and with the arm 120, free to yield in but one direction, and the spring 123 and stop, to operate substantially as described.

9. In a machine for the manufacture of wire-netting, the carriage D, the jaw 107, mounted thereon to slide transversely, and the swivel-studs 113, and means to move the said carriage longitudinally, combined with the rock-shaft 116, and intermediate connecting mechanism between it and the said studs, whereby the outward movement of the jaw may be effected at the proper time in different positions of the carriage D, substantially as described.

In testimony whereof I have signed my name to this specification in the presence of two subscribing witnesses.

BENJAMIN SCARLES.
